SEWING MACHINE LUBRICATION

Herman Ritter, Cranford, and Wilbur J. Peets,
Watchung, N. J., assignors to The Singer Manufacturing Company, Elizabeth, N. J., a corporation of New Jersey

Application February 25, 1950, Serial No. 146,244

12 Claims. (Cl. 112—256)

1

This invention relates to sewing machines and, more particularly, to devices associated with the lubrication of sewing machines and has for its primary object the provision of improved equipment arranged to dispose of excess oil that may collect in a sewing machine.

Another object of the invention is to provide a means for removing excess oil from a sump formed in the bracket-arm head of a sewing machine, which means can be installed in an existing sewing machine with a minimum amount of machine work.

A further object of the invention is to provide a means for removing excess oil from a well in the bracket-arm head of a sewing machine, which means will be economical to install and efficient in operation.

An additional object of the invention is to provide a pump means of the class described, which not only pumps the oil but which also filters the oil as the oil is conveyed by the pump.

With the above and other objects in view, as will hereinafter appear, the invention comprises the devices, combinations and arrangements of parts hereinafter set forth and illustrated in the accompanying drawings of preferred embodiments of the invention, from which the several features of the invention and the advantages attained thereby will be readily understood by those skilled in the art.

In the drawings, which form part of this specification:

Fig. 1 is an elevational, sectional view of a portion of a chain-stitch type sewing machine showing one embodiment of the present invention;

Fig. 2 is an elevational sectional view taken substantially along the line 2—2 of Fig. 1;

Fig. 3 is an exploded perspective view of portions of the mechanism shown in Figs. 1 and 2;

Fig. 4 is a perspective view of the oil sling shown in Figs. 1 and 2;

Fig. 5 is an elevational, sectional view similar to Fig. 1, but showing a second form of the invention as applied to a lock-stitch sewing machine;

Fig. 6 is a view taken substantially along the line 6—6 of Fig. 5;

Fig. 7 is an elevational sectional view taken substantially along the line 7—7 of Fig. 5;

Fig. 8 is an exploded perspective view of portions of the mechanism shown in Figs. 5 through 7;

Fig. 9 is a fragmental, elevational, sectional view similar to Figs. 1 and 5 but showing a third form of the invention;

2

Fig. 10 is a view taken substantially along the line 10—10 of Fig. 9;

Fig. 11 is a perspective view showing elements which also appear in Figs. 9 and 10;

Fig. 12 is a fragmental, elevational sectional view similar to Figs. 1, 5 and 9 but showing a fourth form of the invention;

Fig. 13 is a view taken substantially along the line 13—13 of Fig. 12; and

Fig. 14 is an exploded perspective view of portions of the mechanism shown in Figs. 12 and 13.

Referring more specifically to the drawings, one embodiment of the invention, as applied to a chain stitch type sewing machine, is disclosed in Figs. 1 through 4, showing a sewing machine comprising, a base affording a horizontally disposed work-supporting-plate 12 having an inset throat-plate 13. A conventional feed-dog 14 operates upwardly through openings in the plate 13. A conventional hollow standard (not shown) rises from the work-support 12 and supports an overhanging bracket-arm 15 carrying, at its free end, a hollow bracket-arm head 16 which is normally closed by a removable face-plate 17, having a gasket 18, and held in place by screws 19. Journaled lengthwise of the arm 15 in bearing bushings, one of which is shown at 21, is a main shaft 22 which may be driven by any suitable source of power, as for example a motor (not shown).

At its extreme forward end, the shaft 22 has secured to it, by a set screw 25, a crank-disk 23 carrying a crank pin 24, which through a link 26 and collar 27, transmits reciprocatory motion to an inclined needle bar 28 slidingly mounted in bearings 29 and 31 in the head 16. At its lower end, the needle-bar 28 carries a pair of eye-pointed needles 32—32 which cooperate with other stitch-forming instrumentalities (not shown) but located below the throat-plate 13. A thread take-up, of conventional construction is provided at 34. Also mounted in the head 16, substantially parallel to the inclined needle bar 28 is a bushing 35 for supporting the lower end of a spring-pressed presser-bar 36 which carries, at its lower end, a presser-foot 37.

To lubricate the sewing machine an oil pump, not shown but of standard design, forces oil under pressure into a hollow bore 38 of the shaft 22, one end of the bore being closed by a plug 40. The bearing bushing 21 is lubricated through a radial duct 39 formed in the shaft 22. The duct 39 delivers oil to the end of the bushing 21 nearest the hollow head 16 and the shaft 22 is formed with a spiral groove 41 which forces

oil along the bearing bushing 21 and back into the bracket-arm 15. Most of the oil that may leak from the front end of the bushing 21, is caught by an inner annular groove 43 formed in the bushing 21, and the oil is returned to the inner cavity of the arm 15 by means of an inclined duct or conduit 44 formed in a lower portion of the bushing 21.

In order to lubricate the needle bar actuating mechanisms 24, 26, 27, etc. the shaft 22 is provided with a second radial duct 46 which connects with a radial duct 47 formed in the crank disk 23. The duct 47 is in line with a radial duct 48 formed in the crank pin 24, and the duct 48 connects with a bore 49 formed axially in the pin 24. A pair of radial ducts 51-51 formed in the pin 24 connect the opposite end of the bore 49 with the cooperating bearing surfaces found between the crank pin 24 and the link 26. Some oil is allowed to leak from the bearing surfaces between pin 24 and the link 26 and this leakage oil is sufficient to lubricate the bearing surface of the collar 27.

When the sewing machine is operating, oil is pumped into the bore 38 and oil leaves the bore 38 by way of the ducts 39, 46, 47, 48, bore 49 and ducts 51 and thus lubricates parts within the head 16. Any excess oil which is introduced into the head 16 accumulates in a sump or well 53, formed in the lower part of the head.

The instant invention is concerned with means for efficiently and economically removing oil from the well or sump 53 and returning this excess oil to the cavity within the arm 15 from whence the oil drains to the main sewing machine reservoir (not shown).

The means provided for removing, and at the same time filtering, oil from the well 53 includes a wick 54, of which the lower or receiving end dips into or rests in the well 53, the lower end of the wick being held in position by a support bracket 56 projecting outwardly from the presser-bar bushing 35. The upper or delivery end of the wick 54 is supported by a rectangularly shaped tubular wick-holder 57 which is pivotally supported from a pin or screw 58 carried by a plug 59 held into a stepped aperture 61 formed in the rear face of the head 16, the plug being held to the head 16 by a plurality of screws as 62. The main rectangular body portion 63 of the wick-holder 57 is of proper size to accommodate a doubled portion 64 of the wick 54, and the body portion 63 is provided with an upwardly open, longitudinally extending cutaway aperture 66 which allows the portion of the wick 54, held by the holder 57, to be exposed as at 64 (Fig. 2).

As best seen in Fig. 3, the plug 59 is cylindrical in form having a diameter that is several times its axial length. A raised portion of the plug 59 provides a pair of axially extending bosses 68 and 69, the boss 68 being apertured by an unthreaded hole 71, whereas, the boss 69 is apertured by a threaded hole 72, the two holes being coaxial so that the screw 58, may pass therethrough. The wick-holder 57 has a pair of integrally formed depending flanges 73 and 74, each being apertured by a hole 76, the said holes 76 being the means for pivotally mounting the holder 57 on the screw 58. The flange 73 is relatively long and thereby acts as a guard to hold the wick 54 from contact with the rotary crank disk 23. The pivoted end of the holder 57 has an upwardly inclined arm 77, of which the upper end is doubly notched

as at 78 to accommodate one end of a tension spring 79. The pivoted end of the holder 57 also has a pair of horizontally extending notches 81-81, which, when the holder 57 is mounted as shown in Fig. 2, accommodate the free outwardly extending arm 82 of an L-shaped stop bracket for limiting the pivotal movement of the holder 57, the other arm 83 of the bracket being held to the plug 59 by a screw 84. The upper end of the arm 83 also carries a hook 86 to which is fastened the other end of the aforementioned spring 79. Thus the wick-holder 57 and the wick portion 64, held thereby, are biased upwardly about the pivot pin 58.

When the wick-holder 57 and wick 54 are in the position shown in Figs. 1 and 2, the receiving portion of the wick rests in the sump 53 and the delivery or exposed portion 64 of the wick 54, by reason of the spring 79, is pressed lightly against the lower curved surface of a frusto-conical member or tapered oil sling 87, which is formed integrally with and extends inwardly from the crank disk 23. Since the member 87 is formed integral with the disk 23, it rotates therewith and with the shaft 22. The frusto-conical surface of the member 87 is provided with a spiral groove 88, which as shown, advances in a counter-clockwise direction from the crank disk end of the shaft. When the shaft 22 and the member 87 are rotated in a clockwise direction, as viewed from the crank disk end of the shaft, a pumping action is set up whereby oil, which has risen to the top of the wick by capillary action, is wiped or otherwise removed from the wick portion 64 and conveyed by the combined action of the spiral 88 and centrifugal force which causes oil to move outwardly on the tapered surface of the oil sling to the maximum circumference or discharge edge of the member 87, thus causing oil to move in a direction away from the head of the sewing machine. Centrifugal force produced by rotation of the member 87 causes the oil to be deposited in the stationary annular groove or oil receiving channel 43 surrounding the discharge edge of the sling 87 to catch oil thrown therefrom and from whence it is conveyed by gravity through the conduit 44 to the interior of the arm 15, as heretofore explained.

If it should become necessary to replace the wick 54, the screws 62 are removed and the lower end of the wick 54 is released from contact with the support 56. Then removal of the plug 59 from the aperture 61 removes the wick-holder 57, the wick 54 and all of the parts supported from the plug 59. Thus, there is provided a very convenient means for servicing the oil removing means of the present invention.

Figs. 5 through 8 of the drawings illustrate a second form of the invention as applied to a lock stitch type sewing machine. Parts of the machine shown in Figs. 5 through 8 which are designated by primed numerals of less than 100, as for example set-screw 25' and bearing 29', correspond in function to parts having the same unprimed numerals in the embodiment illustrated in Figs. 1 through 4, and these parts will not in every instance be redescribed in connection with Figs. 5 through 8. Parts of the mechanism shown in Figs. 5 through 8 having numerals between 100 and 130 are particularly associated with this structure and will now be considered.

In order to lubricate the needle bar actuating mechanism located within the hollow head 16' of

Figs. 5 through 8, there is provided a supporting plate 101 which is more fully disclosed in U. S. Patent No. 2,206,285. This plate 101 extends through an aperture 102 in the arm 15' and communicates with a well 103 formed in the arm 15' and the bushing 21'. The plate 101, which is held in place by a screw 104, houses a plurality of wicks 106 having ends located within the well 103 and having their other ends threaded through pipes 107 depending from the plate 101, the second ends of the wicks 106 extending slightly below the lower ends of the pipes 107 into such positions that oil is wiped off by moving parts within the hollow head 16'. When the sewing machine is operating, oil is pumped into the bore 38' in the shaft 22'. Oil leaves the bore 38' by way of the duct 39', saturates the wicks 106 which in turn lubricate parts within the head 16'. The excess oil, together with any other excess oil that may find its way into the head 16', may accumulate in the well or sump 53' formed in the lower part of the head 16'.

The second embodiment of the invention, for removing oil from well 53' and returning it to within the arm 15', includes the wick 54', of which the lower or receiving end rests in the well 53'. The upper or delivery end of the wick 54' is supported by a cylindrical, tube-like wick-holder 108, which is similar to the previously described wick-holder 57, and is pivotally held to the bearing bushing 21' by means of a screw 109 passing through a hole 111 in an upstanding arm 112, the arm 112 being formed integral with and tangent to the cylindrical portion of the holder 108. The main cylindrical body portion of the wick-holder 108 is of proper size to accommodate the delivery end of the wick 54' and is provided with an upwardly open axially extending oval aperture 113, which allows a portion of the wick 54', held by the holder, to be exposed as at 114. A guard arm 116, which protects the wick 54' from the rotating disk 23', is formed integral with and tangent to the cylindrical portion of the holder 108. The arm 116 depends from the holder 108 at a location diametrically opposite the arm 112, heretofore mentioned, the two arms 112 and 116 lying in planes that are parallel and vertical. A helical spring 117, having arms 118 and 119, surrounds the screw 109. The spring 117 biases the holder 108 in a clockwise direction (Fig. 7) about the screw 109 by reason of arm 118 abutting a shoulder 121 formed on the bushing 21' and by reason of the arm 119 abutting the end portion 122 of the wick-holder 108.

When the wick-holder 108 is in the position shown in Figs. 5 and 6, the portion 114 of the wick 54', by reason of the spring 117, is pressed lightly against the curved surface of the frusto-conical member or oil spring 87'. The frusto-conical surface of the member 87' and its spiral groove 88 cooperate to remove oil from the delivery portion 114 of the wick and deposit it in the annular groove 43', from whence it is conveyed to the interior of the arm 15 as previously explained. If it becomes necessary to replace the wick 54' shown in Figs. 5 and 6, the shaft and crank-disk 23' are rotated until a cut away portion of the disk 23' exposes the screw 109. Loosening of the screw 109 permits removal of the wick holder 108 and the wick 54'.

Figs. 9 through 11 of the drawings illustrate a third form of the invention as applied to a machine similar to that shown in Figs. 1 through 4. Parts of the mechanism shown in Figs. 9 through 11, having numerals ranging from 150 through

166, are particularly associated with this structure and will now be described.

In this embodiment of the invention, a bight 151, which is formed intermediate the ends of a portion of a long wick 150, surrounds the oil sling member 87 and forms the delivery portion of the wick, whereas the lower or receiving ends 152 and 153 of the wick rest in the well 53. A wire bracket, which has an eye 154 at one end, is held to the head 16 of the sewing machine by a screw 156. The free end of the bracket is in the form of a U-shaped hook 157 which engages two intermediate portions 158 and 159 of the wick 150 thereby holding the wick from contact with the rotating crank disk 23'. A means for tensioning the wick and thereby holding the bight 151 of the wick in contact with the surface of the oil sling 87 is provided, and comprises a clip 161 having a pair of prongs for each of the downwardly extending portions of the wick 150. The lower end of the clip 161 is apertured and is engaged by one end of a helical spring 162, which is tensioned by having its other end hooked into an aperture formed in the free end of a bracket 163 which is held to the bearing 35 by a screw 164.

The present embodiment of the invention operates in a manner similar to that hereinbefore described. Excess oil, that finds its way to the wall 53, flows by capillary action to the member 87 where it is removed from the wick and carried to the annular groove 43.

If it should become desirable to replace the wick 150, the clip 161 is loosened and then the old wick may be removed. Thereafter a new wick is threaded over the oil sling member 87 and behind the hook 157, this being done without dismantling the sewing machine.

In order to facilitate replacement of the wick 150, a channel 166 has been provided by bevelling the right face (Fig. 9) of the crank disk 23' and by cutting away a portion of the left end of the bearing bushing 21", the disk 23" and the bushing 21" being otherwise similar to the elements 23 and 21 previously described and shown in Figs. 1 and 2. The bight 151 of the wick 150 passes through the channel 166 during the removal and replacement operation. The sewing machine of Figs. 9 and 10 is shown equipped with a plug 59", that is similar to the plug 59 of Fig. 1. The plug 59", however, is not removed during replacement of the wick 150 and, therefore, the plug 59" may be omitted if desired.

Figs. 12 through 14 of the drawings illustrate a fourth form of the invention as applied to a sewing machine similar to that shown in Figs. 1 through 4. Parts of the mechanism shown in Figs. 12 through 14, having numerals ranging from 175 through 202, are particularly associated with this structure and will now be considered.

In this instance, the delivery end of the wick 54 does not come into direct contact with the frusto-conical oil sling 87, but is separated therefrom by an oil conducting felt pad 176, which is substantially in the form of a wedge. The pad 176 and the delivery end of the wick 54 are supported by a wick- and pad-holder having a plurality of parts, including, a box-like housing 177, a solid core 178, a support 179 and a tension spring 181. The upper body portion of the housing 177 has an upwardly open, longitudinally extending, cut-away or aperture 182 which allows the pad 176 to be exposed so that it contacts the member 87. The external left wall (Figs. 13 and 14) of the housing 177 carries a downwardly open hook 183 designed for engagement by the lower

end of the spring 181. The core 178 has an upwardly inclined surface 184 apertured as at 185 by a downwardly extending wick accommodating hole 187. A lug 188 extends below the main portion of the core 178 and this lug enters a notch 189 formed between two lugs 191 and 192 protruding from the left end (Fig. 14) of the support 179. The support 179 also has a downwardly extending bracket 193 apertured by a vertical slotted hole 194 by which the bracket 193 is secured by a screw 196 to a boss 197 formed on inner surface of the bracket head 16. In order to accommodate the holder 177-178-179 the lower portion of a bearing 198, similar to bearing bushing 21, is cut away as at 199 and a pin 200 protrudes from one side of the bearing bushing, the pin 200 acting as an anchor for the upper end of the spring 181. An opening 201 in the head 16 is closed by a plug 202 these being similar to the aperture 61 and plug 59 previously described.

When the parts 177, 178, 179, 181 and 198 are assembled, the upper or discharge end of the wick 54, is held against the bottom of the pad 176, and the top of the pad is held against the lower surface of the member 87, the spring 181 acting to bias the housing 177 upwardly. The operation of this embodiment of the invention is similar to that of the previously described embodiments.

When it becomes desirable to replace the wick 54 or the felt pad 176, the plug 202 is removed, the spring 181 unhooked, and the screw 196 loosened but not removed. Because of the slotted hole 194, the support 179 drops down sufficiently to allow the housing 177 and the core 178 to pass below the member 87 and out of the aperture 201. Then either one of both of the elements 176 and 54 may be easily replaced.

Having thus set forth the nature of the invention, what we claim herein is:

1. In a sewing machine having a frame including a hollow bracket-arm terminating in a hollow head provided with a lubricant-collecting sump, a bearing-bushing at the junction of said head with said bracket-arm and provided in the hollow head side with a lubricant-collecting recess, a horizontally disposed rotary shaft journaled in said bearing-bushing and extending into the hollow head, a rotary member carried by said shaft at the bracket-arm head side of said bearing bushing and extending into said recess, said member being provided with lubricant-feeding means rendered effective upon rotation of said shaft for feeding lubricant toward said recess, a lubricant-conducting wick extending into said sump, holding means for maintaining said wick in oil delivering communication with said rotary member, and conduit means leading lubricant from said recess into said hollow bracket-arm at the opposite side of said bearing.

2. In a sewing machine having a frame including a hollow bracket-arm terminating in a hollow head provided with a lubricant-collecting sump, a bearing bushing at the junction of said head with said bracket-arm and provided in the hollow head side with a lubricant-collecting recess, a horizontally disposed rotary shaft journaled in said bearing-bushing and extending into the hollow head, a frusto-conical rotary member carried by said shaft at the bracket-arm head side of said bearing bushing and having the large diameter portion thereof extending into said recess in such a manner that oil carried by said rotary member is deposited in said recess, a lubri-

cant-conducting wick extending into said sump, holding means for maintaining said wick in oil delivering communication with said rotary member, and conduit means leading lubricant from said recess into said hollow bracket-arm at the opposite side of said bearing.

3. In a sewing machine having a frame including a hollow bracket-arm terminating in a hollow head provided with a lubricant-collecting sump, a bearing-bushing at the junction of said head with said bracket-arm and provided in the hollow head side with a lubricant-collecting recess, a horizontally disposed rotary shaft journaled in said bearing-bushing and extending into the hollow head, a frusto-conical rotary member carried by said shaft at the bracket-arm head side of said bearing bushing and extending into said recess, said member being provided with a spiral groove for feeding lubricant along said frusto-conical member into said recess, a lubricant-conducting wick extending into said sump, holding means for maintaining said wick in oil delivering communication with said rotary member, and conduit means leading lubricant from said recess into said hollow bracket-arm at the opposite side of said bearing.

4. In a sewing machine having a frame including a hollow bracket-arm terminating in a hollow head provided with a lubricant-collecting sump, a bearing-bushing at the junction of said head with said bracket-arm and provided in the hollow head side with a lubricant-collecting recess in communication with said hollow head, a horizontally disposed rotary shaft journaled in said bearing-bushing and extending into said hollow head, a rotary member carried by said shaft and positioned in said hollow head and having a portion extending into said recess, said member being provided with lubricant-feeding means rendered effective upon rotation of said shaft for feeding lubricant toward said recess, a lubricant-conducting wick positioned in said hollow head and extending into said sump, holding means positioned in the hollow head for maintaining said wick in oil delivering communication with said rotary member, and conduit means leading lubricant from said recess into said hollow bracket-arm at the opposite side of said bearing.

5. In a sewing machine having a frame including a hollow bracket-arm terminating in a hollow head provided with a lubricant-collecting sump, a bearing-bushing at the junction of said head with said bracket-arm and provided in the hollow head side with a lubricant-collecting recess, a horizontally disposed rotary shaft journaled in said bearing-bushing and extending into said hollow head, a rotary member carried by said shaft and positioned in said hollow head and having a portion extending into said recess, said member being provided with lubricant-feeding means rendered effective upon rotation of said shaft for feeding lubricant toward said recess, a lubricant-conducting wick positioned in the hollow head and extending into said sump, holding means positioned in the hollow head for engaging said wick, a spring cooperating with said holding means and biasing said wick into oil delivering communication with said rotary member, and conduit means leading lubricant from said recess into said hollow bracket-arm at the opposite side of said bearing.

6. The device of claim 1 in which said means for maintaining said wick in oil delivering communication with said rotary member is a wick-

holder arranged to press a portion of said wick against said rotary member.

7. The device of claim 1 in which said bracket-arm head is provided with an aperture, in which a plug is provided to close the aperture in said bracket-arm head, and in which said holding means is a wick-holder carried by said plug in such a manner that, when said plug is removed, said wick-holder and wick are removed from said bracket-arm head.

8. The device of claim 7 in which said plug has a pair of inwardly extending bosses for pivotally mounting said wick-holder.

9. The device of claim 7 in which said plug has a pair of inwardly extending bosses for pivotally mounting said wick-holder and in which said wick-holder is provided with a guard depending therefrom to protect the wick from damage.

10. The device of claim 1 in which said lubricant-conducting wick is in the form of a bight surrounding said rotatable member.

11. The device of claim 1 in which said means for maintaining said wick in oil delivering communication with said rotary member is a wick-

holder, and in which said wick-holder supports a pad, said pad carrying oil from said wick to said rotary member.

12. The device of claim 1 in which said means for maintaining said wick in oil delivering communication with said rotary member is a wick-holder, said wick holder comprising a boxlike housing having an upwardly open aperture, a solid core having an upwardly inclined surface, and a support having a slotted hole for adjustably supporting the core and the housing.
